UNITED STATES PATENT OFFICE.

JOHN A. WESER, OF NEW YORK, N. Y.

AUTOMATIC PLAYER-PIANO.

1,156,956.

Specification of Letters Patent.

Patented Oct. 19, 1915.

Application filed May 26, 1913. Serial No. 769,849.

To all whom it may concern:

Be it known that I, JOHN A. WESER, a citizen of the United States, residing in the borough of Manhattan of the city of New York, in the State of New York, have invented certain new and useful Improvements in Automatic Player-Pianos, of which the following is a specification, reference being had to the accompanying drawings, forming a part hereof.

10 This invention relates to automatic player pianos and has for an object to provide automatically operated means controlled by a perforation in the music sheet, to stop the travel of the music sheet at a predetermined point.

15 The invention is designed with particular reference to player pianos in which is used a music sheet provided with perforations to form a series of musical compositions adapted to be rendered successively, either upon the introduction of a coin for each piece or upon the proper manipulation of manually controlled devices. In the use of a 20 single sheet having thereon several independent musical compositions it is a matter of primary importance to make the sheet as short as possible and accordingly the margin of waste paper between the last perforations 25 of one piece and the first perforations of the following piece must be as narrow as possible. However, it is a matter of equal importance to stop the movement of the sheet before the perforations of the piece next to 30 be played reach the vents in the tracker board and when the vents in the tracker board are covered, in order that the operating devices may again be set in motion by 35 automatic devices.

40 It is an object of this invention to provide means operated and controlled by the music sheet, which shall stop the travel of the music sheet quickly, shall be invariable in their operation and shall permit the mechanism to be started again automatically.

45 A further object is to provide in combination with the means just referred to, devices controlled by the same perforation which initiates the movement of the pneumatic stopping devices and operable substantially simultaneously with the latter to render inoperative the primary power means employed in the piano player.

50 Other objects will appear hereinafter as this description proceeds, reference now being had to the accompanying drawings for

a detailed description of a practical embodiment of the invention.

In the drawings, Figure 1 is a fragmentary front view of an automatic player-piano embodying the present invention, showing so much thereof as is necessary for a clear understanding of this invention. Fig. 1^a is a fragmentary view in front elevation of a player piano in which the prime mover is an electric motor and embodying the present invention. Fig. 2 is a detail view in section on the plane indicated by the broken line 2—2 of Figs. 1 and 1^a looking in the direction of the arrows, parts being omitted. Fig. 3 is an enlarged view in front elevation showing the tracker-box and its connections showing particularly the means for stopping the rotation of the winding roll. Fig. 4 is a fragmentary view of the same showing the parts in the positions which they assume during the operation of the stopping devices. Fig. 5 is a fragmentary detail view of the winding roll, the music sheet being removed and a portion of the roll being broken away to show the construction thereof, the roll being in its normal operating position or position of rest. Fig. 6 is a view similar to Fig. 5 but showing the roll in the same position in which it is shown in Fig. 4. Fig. 7 is a fragmentary view in side elevation showing the coin slot and associated parts constructed in accordance with the present invention. Fig. 8 is a fragmentary view in front elevation of the parts shown in Fig. 7. Fig. 9 is a view partly in horizontal section showing the arrangement of the electrodes in the coin device with respect to the coin, the pneumatic devices being shown in plan in their normal position. Fig. 10 is a similar view showing the pneumatic devices in operative position to permit the coin to drop to the money box. Fig. 11 is a view in front elevation of the electrodes shown in Figs. 9 and 10, the front insulating plate being removed.

The player-piano *a* illustrated in Fig. 1 is shown as having its main operating motor controlled through a knife switch *b* disposed in any convenient part of the electric circuit *b*², *b*² of the actuating motor *B* of the bellows *B'*, assuming that the motor is electrically operated, although, as this description proceeds, it will be evident that the improvements about to be described are equally applicable to player-pianos or piano-play-

ers controlled through the insertion of a coin or deriving their wind power from manually or foot operated bellows, provision for the foot operation being made, in the 5 illustrated embodiment, in the form of ped-
als B². The motor B is connected opera-
tively to the bellows B' by pulleys B³ and
belt B⁴. The player-piano a has supported
therein in its usual position a tracker-box a'
10 in which is mounted in operative relation to
the music sheet the tracker board a². The
music sheet c as is usual may be carried on
a rewind-roll d and caused to travel over
the tracker board by the rotation of a wind-
15 ing roll e. The rotation of the latter may
be brought about by an air motor f deriving
its power from the main air supply F
and wind-way F', the disposition and na-
ture of the latter being immaterial for a
20 clear understanding of this invention. The
air motor f has suitable operative connec-
tions f' and f² with the winding roll e and
the rewind or carrier roll d respectively.
The form and relative arrangement of the
25 parts thus far mentioned may be as usual
or as desired and a detailed description
thereof need not be set forth here.

This invention is concerned primarily
30 with the quick and invariable stopping of
the music sheet c after the playing of a
piece in accordance with a series of perfora-
tions formed therein and with the restarting
of the same. In the embodiment shown in
35 Figs. 1-4 the music sheet c has formed there-
in perforations constituting successive and
independent musical compositions. It is in
its use with a music sheet of this character
that the present invention is of especial im-
portance. The extent of paper between the
40 last perforation c' of one musical compo-
sition and the first perforation c² of the fol-
lowing composition on the music sheet must
be as short as possible in order that the bulk
of the music sheet may be reduced to a mini-
45 mum. After the last perforation c' of one
piece has passed over its vent in the tracker
board a², the travel of the music sheet must
be interrupted before the first perforation c²
of the succeeding piece comes into operative
50 position over its vent. To effect this stop-
ping of the travel of the music sheet a side
perforation c³ is formed therein which co-
operates with a corresponding vent formed
in the tracker board to initiate the move-
55 ment of special function devices which will
now be described.

At one side of the tracker-box a' within
the piano case is disposed a pneumatic g
of usual type. This pneumatic has its mov-
60 able member connected through a suitable
link g' with a reciprocating plunger g²
mounted in the side of the tracker-box. The
head g³ of the plunger g² is normally in
spaced relationship to the adjacent end
65 flange e' of the winding roll e, so that the

free rotation of the latter in the usual man-
ner with its drive shaft h is permitted.
The roll is mounted loosely on the shaft and
is adapted to be driven thereby through a
suitable clutch. As appears most clearly 70
in Figs. 4 and 5 the shaft h has secured
thereto at its left hand end within the
tracker-box a' a collar h' which has one or
more studs h² adapted to engage a corre-
sponding stud e² projecting from the end 75
flange e' of the roll e. At the other end of
the shaft h, also within the tracker-box a'
is secured a friction disk h³ with which the
adjacent end flange e³ of the winding roll e
is adapted to make frictional contact when 80
the winding roll e is moved longitudinally
along its shaft h to the right as viewed in
Figs. 4 and 5. It is to be noted that the co-
operating studs h² and e² constituting the
clutch engagement of the shaft h with the 85
winding roll e are of such length that when
the roll e is moved to the right (as viewed
in Figs. 4 and 5) said studs will become
disengaged from each other before the end
flange e³ of the winding roll engages with 90
the friction disk h³. The purpose of this
construction will appear later.

From the construction just described and
the relative arrangement of parts, it will
now appear that the purpose of the recipro-
cating plunger g² is to move the winding roll
e to the right (as seen in Figs. 4 and 5) along
95 its shaft h, so that it shall become disen-
gaged from the shaft. The engagement of
the head g³ of the plunger g² with the end
flange e' of the winding roll e brings about
a braking action on the roll so that the roll
is not only freed from its driving shaft h
but its rotation is partially checked. The
travel of the music sheet is checked by the
100 momentary disengagement of the roll e with
its shaft h and the braking action as pointed
out above but it is desirable that the con-
tinued movement of the roll longitudinally
under the action of the plunger g² should
105 bring its end flange e³ into frictional con-
tact with the friction disk h³, to continue
for an instant the rotation of the roll. The
purpose of permitting the roll to be carried
110 on momentarily by the momentum of the
moving parts through its frictional contact
with the friction disk is to insure the travel
of the stopping perforation c² past the vent
in the tracker board so that the travel of the
115 music sheet may be started again automatic-
ally, which would not be the case if this
stopping vent were left uncovered. When
the plunger g² is permitted to return to its
normal position, which happens as soon as
120 the starting vent is covered, the roll e is
moved simultaneously along the shaft h to
its normal position under the action of a
suitable spiral spring i which may be inter-
posed between the end of the roll and the
125 friction disk h³. This movement of the
130

winding roll e to the left (as seen in Figs. 4 and 5) takes it out of frictional contact with the friction disk and into contact with the plunger head, whereby the rotation of the roll is stopped. It also brings the stud e^2 in operative position with respect to the coöperating studs h^2 on the collar h' (the shaft h having come to rest meanwhile), so that the subsequent operation of the primary power means will result in rotation of the winding roll e to bring the perforations of the next musical composition into operative relation with respect to the tracker board a^2 .

It will now appear clearly that when the side perforation c^3 in the music sheet c registers with the stopping vent in the tracker board a^2 the pneumatic g , being operatively connected to said vent through a suitable valve, indicated generally at c^4 , and intermediate tubing c^5 , will be collapsed to move the plunger g^2 to bring about the quick and invariable stopping of the rotation of the winding roll e , in the manner set forth fully above.

In combination with the embodiment in Fig. 1 in which the primary power means is shown as controlled through a knife switch b carried on the casing of the piano a , another pneumatic device, controlled by the perforation c^8 , may be employed to operate simultaneously with the bellows g to break the electric circuit of the prime mover and thus stop the operation of such prime mover and therefore the operation of the air motor f almost simultaneously with the disengagement of the winding roll e from its shaft h . Such a pneumatic device is indicated at j and is shown as having an adjustable stud j' carried on its movable member and adapted to engage the free end b' of the knife switch b to throw the latter so as to break the electric circuit when the bellows j is collapsed. As will appear hereinafter, other devices to interrupt the motor circuit may be employed in combination with the stopping means before described.

The coin controlled devices may be mounted in any suitable part of the casing of the piano a , the mouth k of the slot of course being exposed to receive coins. In the coin chute k' are disposed two spaced electrodes l and l' insulated from each other and carrying suitable terminals l^2 and l^3 respectively to which may be secured the wires leading to the primary actuating electric motor. When a coin is introduced into the coin chute k' it will pass into contact with the electrodes l and l' and bridge the same so as to complete the electric circuit through the primary actuating motor and thus start it. As indicated before this motor, being operatively connected to the main feeder bellows, serves to operate all of the player pneumatic devices. Obviously, the operation of the motor will continue only so long

as the coin bridges the electrodes l and l' and accordingly it is necessary to provide in the chute k' a suitable stop, as m , to limit the movement of the coin during the playing of any one piece. The stop m illustrated herein comprises simply a block pivotally mounted on a stud m' so that it may be oscillated into and out of its operative position with respect to the coin chute. In the preferred embodiment, the stop m is held in position to limit the movement of the coin by a suitable leaf spring n . From the description given it will be evident that the pneumatic devices will continue to operate as long as the motor circuit is completed by a coin and accordingly it is necessary to release the coin from its contact with the electrodes l and l' after the rendition of one or more musical compositions, as may be desired. The releasing devices for the coin are illustrated herein as pneumatically operated, the primary o of the controlling pneumatic o' being in communication with a suitable vent in the tracker board which may have coöperating therewith a suitable special function perforation in the music sheet. On the movable member of the pneumatic o' is carried an arm o^2 in which may be an adjustable abutment o^3 which is adapted to engage and oscillate the stop m , when the bellows o' is collapsed. As pointed out before, the oscillation of the stop m is to permit the coin to drop into the money box.

As will be appreciated, it is often desirable to permit the introduction of a series of coins in the coin chute k' in an automatic player piano which has a continuous music sheet in which are perforations for a series of separate pieces, so that one piece after another may be performed in succession without requiring a coin to be inserted after each piece. Such provision is made by mounting on the movable member of the bellows o' a second arm o^4 which carries at its free end a relatively long pin o^5 , which, when the bellows is collapsed, as shown in Fig. 10, may be moved inwardly to a position beneath one of the coins in the coin chute k' so as to support the same and all above it, when the oscillation of the stop m permits the coin below the pin to drop into the money box. When the bellows o' is permitted to resume its distended position the stop m resumes its normal position in the coin chute k' and the stud o^5 is then withdrawn from its supporting position so as to permit the coin resting thereon to drop to operative position between the electrodes l and l' and thus close the motor circuit and bring about the rendering of the next musical composition on the music sheet. As will be understood, by providing in the music sheet for each piece, a suitable perforation to operate the bellows o' immediately after the piece has been played, the coin which

has brought about the rendering of that piece may be permitted to drop into the money box and the following coin be permitted to drop into operative position to bring about the playing of the next musical composition. Obviously the number of pieces thus played consecutively and continuously is limited only by the number of pieces which may be put on a single music sheet and by the number of coins which are introduced at any one time into the coin chute k' .

Another feature of the invention which will be found to be of great convenience resides in the provision of a program plate p which may have listed on its exposed face the names of the pieces on the music sheet, with corresponding numbers. The music sheet may have printed thereon in the margin between the perforations of successive pieces the corresponding number of the piece next to be played. The program plate has formed therein a suitable sight opening p' which is so placed with reference to the printed piece number on the music sheet, that when the movement of the music sheet is stopped, as by the devices hereinbefore described, the piece number will be exposed to view through the sight opening p' , thus indicating to the observer by reference to the program plate, the name of the piece next to be played. It is desirable to mount the plate p pivotally on a stud q or the like so that the plate may be swung out of position to permit the removal of the music sheet or for other purposes.

Modifications in the details of construction and the relative arrangement of parts herein described will suggest themselves to those skilled in the art, and it is therefore to be understood that the invention is not limited to the precise construction and arrangement shown and described herein.

I claim as my invention:

1. In combination with an automatic motor-operated player piano and a music sheet operatively mounted therein, means to stop the travel of the music sheet, independent means to stop the motor and devices controlled by a perforation in the music sheet to initiate the operation of both said means.

2. In combination with an automatic motor-operated player piano and a music sheet operatively mounted therein, independent pneumatically operated devices controlled by a single perforation in the music sheet to stop simultaneously both the motor and the travel of the music sheet.

3. In combination with an automatic electro-motor-operated player piano the circuit therefor and a music sheet operatively mounted therein, a carrier roll, a winding roll, means to rotate the winding roll, devices to stop the travel of the music sheet and independent devices to interrupt simultane-

ously the circuit, both of said devices being controlled by a single perforation in the music sheet.

4. In combination with a player piano and a music sheet operatively mounted therein, a carrier roll for the music sheet, a winding roll, a drive shaft on which the latter is loosely mounted, means to engage operatively the drive shaft with the winding roll, devices controlled by a perforation in the music sheet to disengage the winding roll from the drive shaft and independent means operable simultaneously to stop the rotation of the drive shaft.

5. In combination with a player piano and a music sheet operatively mounted therein, a carrier roll for the music sheet, a winding roll, means to rotate the winding roll, means to release the winding roll from the rotating means, driving means with which the roll has a frictional engagement after the operation of the releasing means whereby the rotation of the winding roll is continued momentarily in the same direction, and devices to initiate the operation of the releasing means.

6. In combination with a player piano, a carrier roll for the music sheet, a winding roll, means to rotate the winding roll, clutch elements interposed between the winding roll and the rotating means, means to unclutch the winding roll from the rotating means and independent clutch devices operable subsequently to the operation of said unclutching means to engage the winding roll and cause its rotation in the same direction.

7. In combination with a player piano and a music sheet operatively mounted therein, a carrier roll for the music sheet, a winding roll, means to release the winding roll from the rotating means, devices controlled by a perforation in the music sheet to initiate the operation of the releasing means, and devices to engage the winding roll and continue its rotation in the same direction to carry said perforation beyond its vent in the tracker board.

8. In combination with a player piano, a carrier roll for the music sheet, a winding roll, means to rotate the winding roll, clutch elements interposed between the winding roll and the rotating means, means to release the winding roll from the rotating means, and independent devices operable subsequently to the operation of said releasing means to engage the winding roll and continue its movement in the same direction to carry the music sheet to a position where it may be subsequently started automatically upon the actuation of the rotating means.

9. In combination with a player piano and a music sheet operatively mounted therein,

- a carrier roll for the music sheet, a winding roll, a drive shaft on which the winding roll is slidably mounted, means to engage operatively the drive shaft with the winding roll, a frictional disk carried on the drive shaft, means to slide the winding roll along the drive shaft to release the winding roll from the drive shaft and engage subsequently said roll with the frictional disk, and devices controlled by a perforation in the music sheet to initiate the operation of the means to slide the winding roll along the drive shaft.
10. In combination with a player piano and a music sheet operatively mounted therein, a carrier roll for the music sheet, a winding roll, a drive shaft on which the winding roll is slidably mounted, means to engage operatively the drive shaft with the winding roll, a frictional disk carried on the drive shaft, means to slide the winding roll along the drive shaft to release the winding roll from the drive shaft and engage subsequently said roll with the frictional disk, devices controlled by a perforation in the music sheet to slide the winding roll along the drive shaft and a spring to slide the winding roll along the drive shaft in the opposite direction and release the same from engagement with the frictional disk when the releasing means return to normal position.
15. In combination with a player piano and a music sheet operatively mounted therein, a carrier roll for the music sheet, a winding roll, a drive shaft for the winding roll on which the latter is slidably mounted, clutch devices interposed between the winding roll and the drive shaft, a reciprocating plunger mounted operatively with respect to the winding roll, a pneumatic controlled by a perforation in the music sheet, connections between the plunger and the movable member of the pneumatic whereby upon operation of the latter the plunger is moved to slide the winding roll along its shaft to disengage it from the drive shaft and a frictional disk carried on the drive shaft to engage with the winding roll after the operation of the disengaging means.
20. In combination with a player piano and a music sheet operatively mounted therein, a carrier roll for the music sheet, a winding roll, a drive shaft on which the winding roll is slidably mounted, means to engage operatively the drive shaft with the winding roll, a frictional disk carried on the drive shaft, means to slide the winding roll along the drive shaft to release the winding roll from the drive shaft and engage subsequently said roll with the frictional disk, devices controlled by a perforation in the music sheet to slide the winding roll along the drive shaft and a spring to slide the winding roll along the drive shaft in the opposite direction and release the same from engagement with the frictional disk when the releasing means return to normal position.
25. In combination with a player piano and a music sheet operatively mounted therein, a carrier roll for the music sheet, a winding roll, a drive shaft for the winding roll on which the latter is slidably mounted, clutch devices interposed between the winding roll and the drive shaft, a reciprocating plunger mounted operatively with respect to the winding roll, a pneumatic controlled by a perforation in the music sheet, connections between the plunger and the movable member of the pneumatic whereby upon operation of the latter the plunger is moved to slide the winding roll along its shaft to disengage it from the drive shaft and a frictional disk carried on the drive shaft to engage with the winding roll after the operation of the disengaging means.

This specification signed and witnessed this twenty-second day of May, A. D. 1913.
